(57) **CLAIM**

The ornamental design for a folding hand fan rib, as shown and described.

DESCRIPTION

FIG. 1 is a top perspective view of a first embodiment of a folding hand fan rib, showing our new design.

FIG. 2 is a bottom perspective view thereof.

FIG. 3 is a bottom plan view thereof.

FIG. 4 is a top plan view thereof.

FIG. 5 is left-side elevational view thereof.

FIG. 6 is a right-side elevational view thereof.

FIG. 7 is a rear elevational view thereof.

FIG. 8 is a front elevational view thereof.

FIG. 9 is a top perspective view of a second embodiment of a folding hand fan rib, showing our new design.

FIG. 10 is a bottom perspective view thereof.

FIG. 11 is a bottom plan view thereof.

FIG. 12 is a top plan view thereof.

FIG. 13 is left-side elevational view thereof.

FIG. 14 is a right-side elevational view thereof.

FIG. 15 is a rear elevational view thereof.

FIG. 16 is a front elevational view thereof.

FIG. 17 is a top perspective view of a first embodiment of a folding hand fan rib, showing our new design.

FIG. 18 is a bottom perspective view thereof.

FIG. 19 is a bottom plan view thereof.

FIG. 20 is a top plan view thereof.

FIG. 21 is left-side elevational view thereof.

FIG. 22 is a right-side elevational view thereof.

FIG. 23 is a rear elevational view thereof; and,

FIG. 24 is a front elevational view thereof.

The broken lines shown in the figures depict boundary lines of the claimed design.

1 Claim, 24 Drawing Sheets
